UNITED STATES PATENT OFFICE.

CHARLES CROMPTON, OF WORCESTER, MASSACHUSETTS; GEORGE CROMPTON ADMINISTRATOR OF SAID CHARLES CROMPTON, DECEASED.

LOOM.

Application filed November 11, 1919. Serial No. 337,297.

To all whom it may concern:

Be it known that I, CHARLES CROMPTON, a citizen of the United States, residing at Worcester, in the county of Worcester and

5 State of Massachusetts, have invented a new and useful Loom, of which the following is a specification.

This invention has to do with automatic looms, and particularly that class of automatic looms wherein cloth of perfect texture is woven.

It has heretofore been proposed to weave automatically with a filling feeler motion used in conjunction with a bobbin or shuttle 15 replenishing mechanism. In all such looms when the filling breaks the loom is arranged to shut down, and when such a thing happens it is necessary for the weaver to extract the partial pick by hand.

20 It has also heretofore been proposed to extract the broken or exhausted pick automatically, as shown in my application for patent, Serial No. 108,197, filed July 8, 1916, of which Serial No. 245,202 was a continuation, 25 the latter now being Patent No. 1,319,759 dated October 28, 1919. But in this loom while fractional picks are eliminated, it has been found that the first pick from a fresh filling carrier is apt to land in any of a 30 series of sheds. This causes improved but imperfect cloth.

The object of my invention is to improve on that mechanism shown in the above-referred to applications, and I herewith show 35 means not only to extract the broken or partial pick from the shed, but also, to manipulate the shedding motion of a loom in such a way to place the first pick from a fresh filling carrier in the shed from which the broken or partial pick has been extracted.

40 I also show an improved method of extracting the partial pick. In my former applications I showed the extracting mechanism separate from the lay, while in my present application I have arranged this mechanism so that it operates continuously with the lay, as will be fully described in the body of the specification. Similar letters on the drawings represent similar parts.

45 As far as I am aware no loom has yet been proposed which shows means to extract the

partial pick and to supply fresh filling, placing the first shot of filling in the shed from which the imperfect pick has been automatically taken out.

55 With these and other objects in view, my invention consists in a novel combination and arrangement of parts hereinafter described and more specifically pointed out in the appended claims.

60 Referring to the drawings:

Fig. 1 is a front elevation of a portion of a loom having my improvements attached thereto.

Fig. 2 is a plan view of the loom shown 65 in Fig. 1.

Fig. 3 is, on an enlarged scale, a sectional view taken on line 3—3, Fig. 1, looking in the direction of arrow *a*, same figure.

Fig. 4 is, on an enlarged scale, a detail 70 of my improved withdrawing means.

Fig. 5 is a plan view of the parts shown in Fig. 4.

Fig. 6 is, on an enlarged scale, a sectional view taken substantially on line 6—6, Fig. 75 5, looking in the direction of arrow *b*, same figure.

Fig. 7 is a sectional view taken on line 7—7, Fig. 54, looking in the direction of arrow *c*, same figure.

80 Fig. 8 is an end view of the parts shown at Fig. 7.

Fig. 9 is a transverse section taken substantially on line 9—9, Fig. 8.

Fig. 10 is a diagrammatical view of a 85 series of looms, having my attachment secured thereto, and connected to a single receiver for broken ends.

Fig. 11 is a front view of a portion of a loom having the harness holding mechanism 90 attached thereto, the mechanism for removing the broken ends being omitted.

Fig. 12 is a sectional view taken on line 12—12, Fig. 11, looking in the direction of arrow *a*, same figure.

95 Fig. 13 is a detail view of one of the cams.

Fig. 14 is a detail view of the locking block.

100 Fig. 15 is a detail view of the harness locking cam, and,

Fig. 16 is a detail view of the receiving member.

- In the accompanying drawings, 10 and 11 are the loom sides, having the usual breast beam 12 and girt 13, also being provided with a drive shaft 14 and crank shaft 15, 5 which are operated and driven in the usual and well known way. Supported on the bottom shaft 16 are the lay swords 17, and 18, having secured to the upper portion thereof the lay 19 and hand rail 20.
- 10 The above mentioned parts are of the usual and well known construction.
- Secured to the lay 19 is a member 21, said member being provided with an upper and lower track 21^a and 21^b, see Figs. 4, 7, and 8.
- 15 Slidably mounted on the member 21 is a carriage 22 having wheels 22^a and 22^b which engage the tracks 21^a and 21^b of the member 21.
- Said carriage 22 has secured thereto a 20 support 23 for a casing 24, said casing having slidably mounted therein the cutting member 25, said member having, at the upper portion thereof, an opening 25^a, which, when in its upper position, registers with the opening 24^a of the casing 24, thereby forming a continuous passage from the chamber 26^a of the head 26, through the cutting member 25.
- Secured to the lay 19 is a stand 27, said 30 stand having pivoted thereto at 28 a bell crank lever 29 which has pivoted thereto at 30 one end of a horizontally extending lever 31; the opposite end of said lever being pivoted at 32 to the slide member 22.
- 35 Pivoted at 33 to the bell crank lever 29 is the upper end of a connecting rod 34, the lower end of said rod 34 being pivoted at 35 to one end of the cam lever 36, and the opposite end of said cam lever being pivoted at 37 to a stand 38, secured to the cross girt 13, see Figs. 1 and 3.
- Pivoted to the cam lever 36 is a cam roll 36^a which engages and is operated by the cam 40 secured to the drive shaft 14.
- 45 Secured on the shaft 16 is a stand 41 which has pivoted thereto at 42 the lower end of a rod 43, the upper end of which is pivoted at 44 to the coupling 45 which is secured to the cutting member 25. Secured to the cutting member 25 by means of the coupling 45 is one end of a flexible tubing 46, the opposite end of which is directly or indirectly connected with the vacuum device 47, see Figs. 10 and 16.
- 55 I will now briefly describe the operation of the above mentioned parts.
- After the filling (not shown) has been passed through the open shed, and the lay 19 is moving forward for the beat up of the filling, through the movement of the cam lever 36 by means of the cam 40 and connections thereto, the slide 22 is caused to move inwardly, the member 26 being caused to enter the open shed into which the filling has been passed.

On the inward movement of the slide 22, the upper pivoted end of the rod 43 is caused to move to its dead center, thus causing the cutting member 25 to be raised to its upper position in the casing 24 and allowing the opening 25^a to register with the opening 24^a, and thus causing a continuous vacuum passage through the members 25 and 26 through the tubing 46, and into the vacuum receiver 47.

It will be readily seen that should the member 26 engage with a broken end the vacuum would cause said end to be carried into the chamber of the members 25 and 26, and upon the return movement of the cutting member 25, said end would be severed by the registering edges of the openings 24^a and 25^a and thus be carried to the receiving chamber by means of the vacuum.

With the operation of the above, it will readily be seen that it is necessary, for perfect cloth, to retain the particular shed, from which a broken or incomplete pick has been removed in its open position, until a complete pick has been placed therein, therefore for a more complete understanding I will describe my harness holding mechanism separately, referring to Figs. 11 to 15.

Secured to the shaft 14 is a gear 50, which meshes with a gear 51 secured to an auxiliary shaft 52, said shaft being mounted in suitable bearings of stands 53, which are, in this instance secured to the floor. Secured to said shaft 52 is a locking block 54 having a projection 54^a, which engages a recessed portion 55^a of the harness cams 55 which are, in this instance formed integral and loosely mounted on the shaft 52. The harness cams 55 are retained in their engaged position with the block 54^a by means of the compression spring 56, which encircles the shaft 52. Secured to the shaft 52, by means of a sliding key, is a cam 57 which engages a projection 58^a of a lever 58, said lever 58 being pivoted at 59 to a suitable stand 60.

The opposite end 58^b of said lever 58 engages a portion 55^b of the harness cams 55.

The cam 57 is retained in its normal disengaging position, as shown by broken lines, Fig. 11, by means of a compression spring 61, which encircles the shaft 52. Pivoted at 62 to the stand 60 is a lever 63, the lower portion of which is yoked to engage a recess in the hub of the cam 57. The upper portion of said lever 63 has secured thereto, one end of a cord 64, said cord 64 passing, in this instance, around a roll 65, which is pivoted to a suitable stand 66, secured to the loom side 11. The opposite end of the cord 64 is attached to the lower end of a vertically extending lever 67, said lever 67 being pivoted at 68 to a stand 69 secured to the loom side 11. The upper end of the lever 67 has pivoted thereto at 70 the filling

fork 71, said fork having a projection 71^a which is adapted to engage the upper portion 72^a of the lever 72, said lever 72 being pivoted at 73 to the stand 69. The lower end of the lever 72 is provided with a roll 74 which engages the cam 75 secured to the drive shaft 14.

The lever 72 is retained in its engaged position with the cam 75 by means of a tension spring 76, the lever 67 being retained in its normal position by means of the spring 77.

I will now briefly describe, independent of the extracting mechanism, the above mentioned parts pertaining to my harness holding mechanism.

The harness, not shown, is operated in the usual and well known way, by the harness cams 55 which are revolved by means of the gear 50 secured on the drive shaft 14 and the gear 51 secured on the cam shaft 52. The cam 57 is retained in its normal disengaged position, as shown by broken lines, Fig. 11, by means of the spring 61. The lever 58 will also be disengaged from the harness cams 55, the harness cams 55 thereby being caused to rotate with and in the direction of the member 54 secured to the shaft 52.

During the normal operation of the filling, the fork 71 will be lifted, as shown by broken lines, Fig. 12, allowing the lever 72 to be operated by the cam 75 without engaging the portion 71^a of said filling fork 71.

When the filling becomes broken, the fork projection 71^a will remain in the path of the portion 72^a of the lever 72, and carried with said lever 72 in the direction of the arrow, Fig. 12; this, as will be readily seen, will cause the cord 64 to operate the lever 63, thereby causing the lever 63 to move the cam 57 into the engaging path of the projection 58^a of the lever 58.

The projection 58^b of the lever 58, will engage the face 55^a of the cams 55, thereby locking the harness cams 55 and retaining the open shed of the warp in which the filling has become broken and retain the shed in this position until a complete filling is indicated, by the filling fork 71, and the projection 71^a retained out of the path of the portion 72^a of the lever 72.

During the holding of the cams 55 the portion 54^a of the member 54 will become disengaged from the recessed portion 55^b of the cams 55 and through the action of the holding mechanism will revolve with and in the direction of the shaft until such time as the holding mechanism is released thereby allowing the portion 54^a of the member 54 to engage the recess 55^b of the cams 55 and thereby revolve said cams 55 with and in the direction of the member 55 and shaft 52.

In the accompanying drawings, I have

shown the filling fork mechanism on but one side of a loom; it will be readily understood that the same may be applied to both sides of the loom.

From the above combination, it will be seen that I have provided a novel device for removing broken and incomplete picks from the shed and retaining the open shed until a complete pick has been placed therein, thereby making perfect cloth.

The above is adaptable to any of the well known automatic supply looms adapted to change either bobbins or shuttles having the supply mechanism either at one or both ends of the lay.

Having thus described my invention it is evident that many changes and modifications may be made therein by those skilled in the art without departing from the spirit and scope thereof, therefore I do not wish to be limited to the specific details herein disclosed, or to the application of the devices to either one end or both ends of the lay, and what I claim is:

1. A loom, having a shuttle, picking means to lay the filling of said shuttle in the shed of the loom, and means carried by the lay of said loom to withdraw a broken or incomplete pick intact.

2. A loom, having a shuttle, picking means to lay the filling of said shuttle in the shed of the loom, and pneumatic means positioned at opposite sides of said shed and carried by the lay of said loom to engage and withdraw a broken or incomplete pick.

3. A loom, having a shuttle, picking means to lay the filling of said shuttle in the shed of the loom, and means secured to the lay and positioned to enter said shed to engage and withdraw a broken or incomplete pick as an entirety.

4. A loom, having a shuttle, picking means to lay the filling of said shuttle in the shed of said loom and means carried by said lay and adapted to enter said shed to engage and withdraw horizontally a broken or incomplete pick.

5. A loom, having a shuttle, picking means to lay the filling of said shuttle in the shed of said loom, and means carried by said lay at opposite sides of said shed and adapted to enter said shed alternately to engage and withdraw horizontally, before beat-up, a broken or incomplete pick.

6. A loom, having a shuttle, picking means to lay the filling of said shuttle in the shed of the loom, and means carried by said lay adapted to enter said shed and withdraw in a substantially horizontal direction from the shed before beat-up the two ends of a broken pick.

7. A loom, having a shuttle, picking means to lay the filling of said shuttle, and broken or incomplete pick withdrawing

- means, carried by the lay, adapted to enter the end of the shed before beat-up and to withdraw therefrom a broken or incomplete pick as an entirety.
- 5 8. A loom, having a shuttle, picking means to lay the filling of said shuttle, and broken or incomplete pick withdrawing means, carried by the lay, adapted to enter the ends of the shed before beat-up and to withdraw 10 therefrom the two ends of a broken or incomplete pick.
9. In an automatic loom, a warp, harness changing means to form a shed of said warp, a shuttle, picking means to lay the filling 15 carried by said shuttle in said shed, means adapted to indicate a broken or incomplete filling in said shed and operative to retain said shed in its open position and means for removing a said broken or incomplete pick 20 from said open shed the continuing operation of the loom bringing the fresh and complete pick in said open shed.
10. In a weft replenishing loom, a warp, harness changing means to form a shed of 25 said warp, a shuttle, picking means to lay the filling carried by said shuttle in said shed, filling indicating means adapted to engage said filling and upon indication of a broken or incomplete filling to retain said 30 shed in its open shed and means for automatically removing a broken pick from said open shed, the loom meanwhile continuing in operation.
11. In a weft replenishing loom, a warp, harness changing means to form an open 35 shed of said warp, a shuttle, picking means to lay the filling carried by said shuttle in the open shed, filling indicating means adapted to indicate a broken or incomplete 40 filling in said open shed, and adapted to retain the open shed until a complete filling has been placed therein, and means adapted automatically to remove said broken or incomplete pick, whereby the operation of the 45 loom is uninterrupted and a perfect pick of filling is brought into the same shed from which the imperfect pick was removed.
12. In a weft replenishing loom, a warp, harness changing means to form a shed of 50 said warp, a shuttle, picking means to lay the filling carried by said shuttle in said warp, means adapted to engage said filling before beat-up and upon indicating a broken or incomplete filling to retain said shed 55 in its open position, and means adapted to remove said broken or incomplete pick from said shed, said indicating means being effective to cause resumption of the normal shedding operation when a fresh and complete pick has been placed in said shed from 60 which the broken filling was removed, thus producing perfect fabric without stopping the loom.
13. In a weft replenishing loom, a warp, harness changing means to form a shed of 65 said warp, a shuttle, picking means to lay the filling carried by said shuttle in said shed, pick indicating means to engage the filling before beat-up and operative upon indication of a broken or incomplete filling 70 to retain said shed in its open position until indication of a complete pick of filling in the specific open shed, and means for automatically removing said broken or incomplete pick from said open shed before the 75 complete pick has been placed therein, thus permitting the loom meanwhile to continue in operation.
14. In a weft replenishing loom, a warp, harness changing means to form a shed of 80 said warp, a shuttle, picking means to lay the filling carried by said shuttle in said warp, filling indicating means disposed at opposite sides of said shed and adapted upon indication of a broken or incomplete 85 filling to retain said shed in its open position until indication of a complete filling in said shed, and means for automatically removing said broken or incomplete pick from said shed, thereby making possible the production of perfect cloth without knocking off the loom.
15. In a device for removing broken filling threads from the warp of a loom the combination with the lay and a guiding means extending longitudinally thereof crosswise the loom, of a slide movable on said guiding means at each end of the loom, and a suction device carried by each slide for removing the broken filling threads. 90
16. In a device for removing broken threads from the shed of a loom, the combination of the lay, a guide extending along the lay, a slide movable on said guide, a cam timed to move (with) the lay, means 105 connected with the cam for moving the slide inwardly toward the center of the loom as the lay is about to beat up after the shuttle is thrown.
17. In an automatic loom, a lay, shed forming mechanism, a shuttle to deposit weft in a shed formed on said lay, weft extracting means adapted to enter said shed and to extract from it a broken or incomplete pick, and means operative upon occurrence of such broken or incomplete pick to control the shed forming mechanism so as to bring the new pick in the proper empty shed while continuing the loom in operation. 110
- In testimony whereof I have hereunto set 120 my hand.

CHARLES CROMPTON.
